UNITED STATES PATENT OFFICE.

ROBERT N. GOWELL, OF ASHBURNHAM, MASSACHUSETTS.

ROAD-SCRAPER.

SPECIFICATION forming part of Letters Patent No. 311,482, dated February 3, 1885.

Application filed June 6, 1884. (No model.)

To all whom it may concern:

Be it known that I, ROBERT N. GOWELL, of 5 Ashburnham, in the county of Worcester, State of Massachusetts, have invented a certain new and useful Improvement in Road-Scrapers, of which the following is a description sufficiently full, clear, and exact to enable any person skilled in the art or science to which said invention appertains to make and 10 use the same, reference being had to the accompanying drawings, forming a part of this specification, in which—

Figure 1 is a top plan view of my improved scraper; Fig. 2, a bottom plan view of the 15 same; Fig. 3, a vertical longitudinal section, and Fig. 4 a rear end elevation.

Like letters and figures of reference indicate corresponding parts in the different figures of the drawings.

20 My invention relates to that class of road-scrapers in which the scraper proper is adjustable both vertically and laterally; and it consists in a novel construction and arrangement of the parts, as hereinafter more fully 25 set forth and claimed, by which a more effective and desirable article of this character is produced than is now in ordinary use.

The nature and operation of the improvement will be readily understood by all 30 conversant with such matters from the following explanation.

In the drawings, A represents the main frame or body of the machine, which is mounted at its forward end on the small wheels Y, 35 and at its rear end on the large wheels X, journaled, respectively, on the axles Z and &, the forward axle being provided with the fifth-wheel or plate q, king-bolt r, and tongue or pole j.

40 Projecting downwardly from near either end of the frame A there is a centrally-disposed bar or lug, V, provided with an elongated vertical slot, v, the lower end of the slot being closed by the cross-bar t, and disposed 45 beneath said frame between the axles Z & there is an auxiliary frame, N, carrying the scraper U. The auxiliary frame is rectangular in shape, and is suspended by means of a centrally-disposed pin or stud, u, at either 50 end, the studs projecting into the slots v of the lugs V and resting on the cross-bars t, thereby journaling the frame so that it may

be tilted or partially rotated laterally in either direction.

Projecting upwardly from a cross-bar, C, 55 near the forward part of the frame A, and at each end of the same, there is a standard, E, carrying a centrally-pivoted lever, H,

A cross-bar, D, is mounted on the rear portion of the frame A, and projecting upwardly 60 from each end of this bar there is a standard, F, carrying a centrally-pivoted lever, I, and also an eccentrically-pivoted lever, J, the long arms of the levers J extending backwardly over a step, B, connected with the 65 rear end of the frame A, and designed to be occupied by the operator of the machine.

The forward corners of the frame N are respectively connected to the forward ends of the levers H by rods h, the rear corners of 70 said frame being also respectively connected to the rear ends of the levers I by the rods p.

The inner or adjoining ends of the levers I H are connected or jointed together by the links or rods l, and the inner ends or short 75 arms of the levers J are respectively pivoted or jointed to the latter rods near their centers.

A standard, G, is mounted on the cross-bar b of the frame N, and centrally pivoted in this standard there is a lever, K.

80 A rocker-shaft, O, is journaled horizontally in the forward end of the frame N, and provided with the centrally-arranged arm n, and at either end with an arm P, the arm n being connected with the forward end of the lever K by a rod, i.

A cross-bar, T, is centrally disposed on the frame N, this bar being provided with an elongated slot, w, and carrying a slide, S.

Disposed beneath the frame N there is a 90 V-shaped frame, Q, provided with the vertically-arranged stud or journal R, which projects upwardly through the slot w and slide S, and is provided with a pin, y, which passes through its upper end above said slide, the 95 frame Q being suspended on said stud.

Attached to the lower side of the frame Q there is a transversely-arranged share, U, or scraper proper, provided with the braces k.

Journalized vertically in the rear end of the 10 frame N, and adapted to be raised and lowered therewith, there is a shaft, r, provided at its upper end with the wheel L, and at its lower end with the drum W.

Attached to the forward part of the frame N, at each side thereof, is a plate, 34, having its rear end curved or rounded, as shown at 35 in Fig. 2.

5 A cross-bar, 36, connects the side pieces of the V-shaped frame Q, the side pieces being considerably thicker than the bar, which is proportioned to permit the plates 34 to pass freely over the same in turning said frame to 10 adjust the scraper U.

Inclosed between the frame Q and the cross-bar 36 there is a suitable flooring or other frame-work for supporting the stud or journal R, as best seen in Fig. 3.

15 A flange or lip, 37, projects inwardly from the ends of either side piece of the frame Q, these flanges being respectively adapted to enter mortises (not shown) in the forward end of the frame N, and thereby aid in supporting 20 the frame Q when the scraper U is arranged diagonally to the frame N and in use.

A cord or chain, d, has its central portion wrapped around the drum W, each of its respective halves or sections being thence carried around a sheave, g, in the rear end of the frame N, and inwardly over a pulley, f, in the apex of the frame Q, at which point they pass or cross each other, their ends being respectively fastened to the side pieces of the frame 30 Q, as seen at e, Fig. 2.

The machine is provided with a seat, A², near the forward end of the main frame, for the use of the driver, also with a bar, J², for securing or holding the auxiliary frame at any 35 desired angle when the scraper proper is tilted.

In the use of my improvement the operator of the machine stands on the step B and raises or depresses the scraper U, as occasion requires, by means of the levers J. By raising 40 the outer ends of the levers J the inner ends of the levers I H will be depressed, thereby drawing up the rods p h and elevating the frame N and scraper U, and vice versa. It will be obvious that when but one of the levers J is raised or depressed one side of the frame N, and consequently one end of the scraper U, will be correspondingly raised or depressed, and that when both of said levers are raised or depressed simultaneously both 45 ends of the scraper will be raised accordingly.

The lateral adjustment of the scraper is effected by turning the shaft r, the shaft being held in any desired position by a ratchet-wheel, M, and pawl m, the ratchet being secured on the shaft and the pawl pivoted to the frame of the machine. The scraper being at right angles to the frames A and N, as seen in Fig. 1, if, now, the wheel L is turned to the right, that section of the cord d which is 50 marked d² will be wound onto the drum W, and that marked d' will be unwound, thereby causing the stud R to traverse in the slot w from the right to the left hand side of the machine, and the scraper to assume the diagonal position indicated by the dotted lines in Fig. 2.

2. The plates 34 are not flush with the side

pieces of the frame N, but there is sufficient space between the sides of said plates and the sides of said frame to respectively receive the side pieces, 40 and 41, of the frame Q, so 7c that when the scraper is adjusted, as shown by the dotted lines in Fig. 2, the side piece, 40, of the frame Q will rest against the outer side of its plate 34, in which position it is securely fastened by depressing the lever K, 75 thereby turning the rocker-shaft O and causing the arms P to assume a vertical position. It will be obvious that when the side piece, 40, of the frame Q is locked in position at the side of its plate 34 by one of the arms P the 80 opposite side piece, 41, will stand at right angles to the sides of the frame N, and the scraper U will stand diagonally to said frame. If, now, the lever K is raised, the side piece, 40, released, and the wheel turned to its left to the 85 fullest extent, the cord d will be wound onto the drum W in the opposite direction from that described, causing the stud R to traverse from the left to the right hand side of the machine, the side piece, 41, to be brought against 90 its plate 34 and the scraper U to assume a diagonal position with respect to the frames A N precisely opposite that indicated by the dotted lines in Fig. 2.

From the foregoing it will be obvious that 95 the scraper proper may be readily adjusted laterally at any desired angle by means of the wheel L, and vertically at any desired height by means of the levers J, or tilted endwise by using but one of the latter levers.

Having thus explained my invention, what I claim is—

1. In a road-scraper, the combination of the following instrumentalities, to wit: a main frame mounted on wheels, an auxiliary frame 105 disposed beneath the main frame, and supported thereby, said auxiliary frame being adapted to be tilted or rocked laterally, and also raised and lowered vertically, a scraper proper disposed on a frame beneath the auxiliary frame, and supported thereby, said scraper proper being thus adapted to lateral and vertical adjustment and to be tilted endwise, means for locking or securing the frame carrying the scraper proper at any desired 115 height, means for locking or holding the scraper proper at any desired angle when the same is tilted, means for raising, lowering, and tilting the auxiliary frame, and means for adjusting the scraper proper vertically and laterally, 120 and also tilting the same endwise, substantially as described.

2. In a road-scraper, the auxiliary frame N, provided with the studs u, in combination with the main frame A, provided with the slotted lugs V, the scraper U, means for raising and lowering the frame N, and means for adjusting the scraper laterally, substantially as set forth.

3. In a road-scraper, the main frame A, 130 mounted on the wheels Y X, and provided with the slotted lugs V, pole j, and step B, the

auxiliary frame N, having the slotted bar T, cap S, and plates 34, the V-shaped frame Q, carrying the scraper U, and provided with the stud or journal R, the shaft r, provided with the drum W, cord d, ratchet M, pawl m, and wheel L, the rocker-shaft O, provided with the arms P and arm n, the lever K, mounted in the standard b, and provided with the rod i, the levers H, mounted in the standards E, the levers I J, mounted in the standards F, the rods h p, and links l, combined and arranged to operate substantially as described.

4. In a road-scraper, the frame Q, provided with the flanges 37, in combination with the frame N, having the plates 34, and shaft O, having the arms P, substantially as set forth.

5. In a road-scraper, the levers H I J, in combination with the frame N and rods h p l, substantially as set forth.

6. In a road-scraper, the rocker-shaft O, having the arms P n, in combination with the lever K, and rod i for locking the frame Q, substantially as described.

7. In a road-scraper, the slide or cap S, in combination with the bar T, stud R, pin y, frame Q, scraper U, and means for operating said scraper, substantially as described.

ROBERT N. GOWELL.
